(57) **CLAIM**

The ornamental design for an inferior turbine elevator, as shown and described.

DESCRIPTION

This invention was made with government support under grant number 5R25EB021894 awarded by The National Institutes of Health. The government has certain rights in the invention.

FIG. 1 is a perspective view of an inferior turbine elevator showing our design;

FIG. 2 is a top plan view of an inferior turbine elevator of FIG. 1;

FIG. 3 is a bottom plan view of an inferior turbine elevator of FIG. 1;

FIG. 4 is a right side view of an inferior turbine elevator of FIG. 1;

FIG. 5 is a left side view of an inferior turbine elevator of FIG. 1;

FIG. 6 is a front view of an inferior turbine elevator of FIG. 1; and,

FIG. 7 is a rear view of an inferior turbine elevator of FIG. 1.

The broken/dotted lines are directed to environment and are for illustrative purposes only; the broken lines form no part of the claimed design. The innermost unshaded surface in the view of FIG. 3 forms no part of the claimed design.
